EXPANSIBLE DRILLING DEVICE

Martin E. True, George Boer, and Wallace M. O'Reilly, Houston, Tex., assignors, by mesne assignments, to Esso Research and Engineering Company, Elizabeth, N.J., a corporation of Delaware

Application September 14, 1956, Serial No. 609,918

10 Claims. (Cl. 255—76)

The present invention is directed to a drilling and reaming device which is movable through a well tubing. More particularly, the invention is directed to a drilling and reaming device lowerable through a well tubing and which is expansible to drilling or reaming position. More particularly, the invention is directed to a device which is lowerable through a well tubing into a well casing and is expansible into the opened position for reaming out a well casing or for drilling or reaming out a well bore and the like.

The present invention may be described as a drilling or reaming device lowerable through a well tubing on a flexible member, such as a wire line, which comprises, in combination, a retrievable support member which carries a slidable sleeve member having at least one pair of expansible drilling or reaming blades pivotally connected to the sleeve member. The drilling blades may have both drilling and reaming surfaces thereon. Frangible means releasably attach the blades to the sleeve member in inoperative position during the lowering through the well tubing. The sleeve member is slidably arranged for relative movement of the support member. The support member is provided with upwardly inclined surfaces matingly engaging with corresponding inclined surfaces on the expansible blades. Biasing means urge the sleeve upwardly relative to the support member for expanding the blades into operative position on release of the frangible means.

The sleeve member may suitably be provided with means on its lower end engageable with the bottom of the well to release the frangible means. The frangible means may suitably be a shear pin. The means on the lower end of the sleeve member may suitably be a trip bar or may be a drill connected to the lower end of the sleeve member such that when the bottom strikes against the bottom of the well the shear pin is ruptured. When the means on the lower end of the sleeve member is a drill, it is suitably arranged to project ahead of the expansible blades such that it may drill a hole ahead of the expansible blades.

It is contemplated that the retrievable support member may be provided with a fluid passageway therethrough having an inlet and an outlet. Also, the support member may be provided with a packing means mounted on the support member intermediate the inlet and outlet for sealingly engaging with the wall of the tubing. The packing means may be provided with pipe engaging means, such as pipe slips, which are forced into engagement with the wall of the tubing on imposition of fluid pressure on the packing means. The support member is movable vertically relative to the packing means when the packing means engages with the wall of the tubing.

The retrievable support member is also suitably provided with a fishing head on its upper end engageable with a fishing tool which may suitably be provided on the end of a flexible member, such as a wire line, cable, and the like. The support member may be provided with

2

a weight member arranged on the support member to provide weight for the device.

It is contemplated in the practice of the present invention that the device may be supplied with either or both first and second pairs of expansible blades each pivotally connected to the sleeve member and each releasably attached by a frangible means to the sleeve member to hold the blades in inoperative position during the lowering operation through the tubing. It is contemplated that one of the pair of blades may be pivotally connected to the sleeve member approximately 90° from the first pair of blades and that the second pair of blades may be vertically spaced apart on the sleeve member from the first pair of blades. Any one or both of the pairs of blades may be provided with a reaming surface or the lower pair of blades may be provided with a drilling surface or both a reaming surface and a drilling surface.

The present invention will be further illustrated by reference to the drawing in which:

Fig. 1 shows a partial view of the lower portion of the device of the present invention lowerable through the tubing string in a well casing in the inoperative position;

Fig. 2 is a view partially in section of the upper portion of the device of Fig. 1;

Fig. 3 is a view partially in section of the device of Fig. 1 in operating position;

Fig. 4 is a side view in elevation of Fig. 3;

Fig. 5 is an elevational view of the upper portion of the device as shown in Fig. 2;

Figs. 6 and 7 are views of the upper and lower sections of a modified device of the present invention; and Fig. 8 is a view taken along the line 8—8 of Fig. 6.

Referring now to the drawing and particularly to Figs. 1 to 3, in which identical numerals will be employed to designate identical parts, numeral 11 designates a well tubing arranged in a casing 12 with the well tubing 11 being arranged above the uppermost of a plurality of productive hydrocarbon formations, not shown, in accordance with the permanent well completion technique, such as described in World Oil, March, 1954. In Fig. 1 a tubular support member 13 has arranged thereon a slidable sleeve 14 which is biased upwardly by a biasing means, such as a helical coil spring 15. The support member 13 is provided with a first inclined surface 16 and a second inclined surface 17 which are adapted to matingly engage with inclined surfaces 18 and 19 on the upper ends 20 and 21 of expansible blades 22 and 23. The expansible blades 22 and 23 are pivotally attached to the sleeve member 14 by means of a pivot pin 24.

Attached to the lower end of the sleeve member 14 is a suitable drill member 25, such as one of the bladed-type provided with a cutting edge 26. Other types of drill members may be provided as desired. The upper end of the spring 15 is confined within a space 27 in the upper end of the sleeve 14. The sleeve 14 is attached to a ring member 29 by mating threads 30 and the tubular support member 13 is attached by mating threads 31 to a collar 28 which serves to connect by mating threads 32 to an upper portion 33 of the support member 13.

The support member may be provided with or may carry a suitable weight member. For example, collar 28 may be suitably weighted to provide weight for the device. It is to be noted that collar 28 is attached to support member 13 by threads 31 and 32. Tubular support member 13 is slidably arranged for relative movement through ring member 29. The support member 13 is provided with a longitudinal passageway 34 which extends therethrough and which is provided with an inlet 35 and an outlet 36 which discharges just above the blades 22 and 23.

A cup packer 38a is slidably arranged on the portion 33 below inlet 35. Arranged below cup packer 38a is a packing means

generally indicated by the numeral 37 provided with a downwardly facing cup-type packer 38 which is provided with slip members 39. The packing member is sealingly and slidably arranged on the upper section 33 of the support member 13 by sealing means, such as O-rings 40. Fluid pressure imposed upwardly against the cup packer 38 expands the packer 38 and the pipe slips 39 into sealing engagement with the inner wall of the tubing 11.

The upper end of the section 33 has a fishing head 42 attached thereto to which is attached a wire line or flexible member 44. In Fig. 1 a shear pin 45 extending through sleeve 14 holds the blades 22 and 23 in inoperative position when the device is lowered through the well tubing 11.

Referring now to Fig. 6 in which parts identical to those of Figs. 1 through 5 are identified by identical numerals, a modified type of device is illustrated lowerable through a well tubing 11 into a casing 12 as shown in Fig. 1. In this arrangement, a sleeve member 50 has pivotally attached thereto by means of a pivot pin 24, blades 51 and 52, each having an upper surface 18 and 19 engageable with mating surfaces 16 and 17 of support member 57 which is similar to the supporting members 13. In this embodiment of the device, the sleeve member 50 is biased upwardly by means of a biasing means 15 arranged within a space 27 in the upper end of the sleeve 50. The sleeve 50 is connected by mating threads 30 to an annular ring member 29. The support member 57 is connected by mating threads 31 to a collar 28, such as described in Figs. 1 to 5. Although supporting member 57 may be tubular it is shown as a solid rod.

The blades 51 and 52 are provided on their lower ends with a cutting surface, such as 63 and 64, and a reaming surface 65 and 66.

As shown in Fig. 7, a second set of reaming blades 51 and 52 are vertically spaced below the upper set and are pivotally connected by a pivot pin 24 to a second sleeve member 50 which is slidably arranged on a second support member 57 which is biased upwardly by a second biasing means, such as 15. The second support member 57 threadedly connects by mating threads 68 to the lower end 69 of the upper sleeve member 50.

The lower end 70 of the lower sleeve member 50 may suitably be provided with a trip bar 71 which is designed to strike the bottom of the hole or suitable obstruction in the wellbore casing 12.

It is to be noted that casing 12 has been perforated to form perforations 80 which have been sealed with plugs 81 of cement which project into the casing 12 in the form of buttons, nodules or rivet heads 82 of cement.

While the upper end of the device of Figs. 6 and 7 has not been shown, it may be constructed identically with the device of Figs. 1 to 5.

The device of the present invention is useful in permanent well completion operations of the nature described in the aforementioned World Oil reference. In such permanent well completion operations as during perforating or cementing, burrs or buttons or nodules of cement may be left in the casing and form an obstruction which it is desirable to remove. The present invention allows the removal of such obstructions by a reaming or redrilling action. In accordance with the device of Figs. 1 to 5, the structure is lowered on a wire line or cable 44 through the tubing 12. The annulus A between the tubing 11 and the casing 12 has been closed by a suitable packing arrangement, such as 72, which may be a packer of the type described in the Composite Catalog of Oil Field and Pipe Line Equipment, vol. 1, page 850, 1955-56 edition. In this instance, the tubing 11 is provided with a side port 73 communicating a passageway 74 in the member 75 with the annulus A.

If the device of the present invention is lowered through the tubing, pressure imposed from the annulus A through port 73 causes the cup-type packer 38 and the pipe slips 39 to engage with the inner wall of the tubing.

As the drill 25 strikes the bottom of the hole, the shear pin 45 is ruptured by the weight and the tapered surfaces 16 and 17 of support member 13 acting downwardly against the tapered surfaces 18 and 19 of the blades 22 and 23 as the bit 25 and the sleeve strike the bottom of the hole and thus causing the spring 15 to move the sleeve 14 upwardly on the support 13 and allowing the blades 22 and 23 to expand outwardly. Since the support member 14 is movable with respect to the packer 38 and slips 39, manipulation of wire line 44 allows the whole device to be rotated and reciprocated upwardly and downwardly by the spring or twist in wire line 44 to remove burrs or plugs, such as 82, which project into the casing, as shown in Fig. 7. After the burrs or plugs have been removed, during which time the drill 25 may be employed to drill ahead to remove any bridging obstructions in the casing due to bridging over of cement, and the like, the whole device may be raised through the tubing. As the upper ends 20 and 21 of the expanded blades strike the lower end 76 of the tubing, the blades 22 and 23 pivot about the pivot pin 24 into a retracted position and are held thereby by the inner walls of the tubing 11. Release of pressure from the annulus A or from the tubing 11 allows the packer 38 and the slips 39 to become disengaged and, therefore, the whole structure is removable through the tubing.

When employing the device of Figs. 1 to 5, it is possible by virtue of the passageway 34 and inlets 35 and outlets 36 to circulate drilling fluid such as mud or water down the tubing 11 into the region of the blades 22 and 23 to remove cuttings and debris. Location of packing member 37 intermediate the inlet 35 and outlet 36 allows the drilling fluid, debris and cuttings to be circulated out through the lower end of tubing 11 below the packing member 37, through the port 73 and passageway 74 into annulus A and thence to the well head at the earth's surface not shown. Imposition of fluid pressure through the tubing 11 and passageway 34 also holds the packing member 37 into sealing engagement with the inner wall of the tubing 11.

The device of Figs. 6 to 8 operates similarly to that of Figs. 1 to 5.

While the invention has been described relative to drilling out obstructions through the casing and to reaming the wall of the casing, it is also applicable to reaming out the wall of a well bore and to drill in an open hole. Thus the device of the present invention may be used to drill a small hole ahead of the reaming blades, the small hole then being reamed out as drilling proceeds. Therefore, it is desired that the present invention not be limited to the particular examples given by way of illustration thereof.

The present invention is quite useful and advantageous in that a tool or drilling device is provided which may be lowered through a well tubing and used to ream out well casing and well bores without moving the tubing. In other words, operations of the nature described herein may be carried out by wire line without manipulating the tubing.

The nature and objects of the present invention having been completely described and illustrated, what we wish to claim as new and useful and to secure by Letters Patent is:

1. A device for use in a well and lowerable through a well tubing string which comprises in combination, a retrievable support member, a sleeve member slidably arranged on said support member, at least a pair of expandable blades pivotally connected to said sleeve member, frangible means releasably attaching said blades in inoperative position to said sleeve member, said support member enclosing the upper ends of said blades and being provided with upwardly inclined surfaces matingly engaging with corresponding inclined surfaces on said blades, and biasing means urging said sleeve upwardly relative

to said support member for expanding said blades into operative position on release of said frangible means.

2. A device for use in a well and lowerable through a well tubing string which comprises, in combination, a retrievable support member, a sleeve member slidably arranged on said support member, at least a pair of expandable blades pivotally connected to said sleeve member, frangible means releasably attaching said blades in inoperative position to said sleeve member, said support member enclosing the upper ends of said blades and being provided with upwardly inclined surfaces matingly engaging with corresponding inclined surfaces on said blades, biasing means urging said sleeve upwardly relative to said support member for expanding said blades into operative position on release of said frangible means, and means on the lower end of said sleeve member engageable with the bottom of the well whereby inertia of the support member applying force to said blades ruptures said frangible means when the means on the lower end of the sleeve has its downward movement stopped on engaging the bottom of the well.

3. A device for use in a well and lowerable through a well tubing string which comprises, in combination, a retrievable support member, a sleeve member slidably arranged on said support member, at least a pair of expandable blades pivotally connected to said sleeve member, frangible means releasably attaching said blades in inoperative position to said sleeve member, said support member enclosing the upper ends of said blades and being provided with upwardly inclined surfaces matingly engaging with corresponding inclined surfaces on said blades, biasing means urging said sleeve upwardly relative to said support member for expanding said blades into operative position on release of said frangible means, and drilling means on the lower end of said sleeve member engageable with the bottom of the well whereby inertia of the support member applying force to said blades ruptures and releases said frangible means to drill ahead of said blades when the drilling means on the lower end of the sleeve has its downward movement stopped on engaging the bottom of the well.

4. A device for use in a well and lowerable through a well tubing string which comprises, in combination, a retrievable support member having a fluid passageway therethrough provided with an inlet and an outlet, a sleeve member slidably arranged on said support member, at least a pair of expandable blades pivotally connected to said sleeve member, frangible means releasably attaching said blades in inoperative position to said sleeve member, said support member enclosing the upper ends of said blades and being provided with upwardly inclined surfaces matingly engaging with corresponding inclined surfaces on said blades, biasing means urging said sleeve upwardly relative to said support member for expanding said blades into operative position on release of said frangible means, packing means mounted on said support member intermediate the inlet and outlet for sealingly engaging with the wall of said tubing, and drilling means on the lower end of said sleeve member engageable with the bottom of the well whereby inertia of the support member applying force to said blades ruptures and releases said frangible means to drill ahead of said blades when the drilling means on the lower end of the sleeve has its downward movement stopped on engaging the bottom of the well, said support member being movable vertically relative to said packing means when said packing means are engaged with the wall of the tubing.

5. A device in accordance with claim 4 in which the

packing means is provided with pipe engaging means for engaging with the wall of the well tubing and in which said packing means and said pipe engaging means are operative by fluid pressure imposed on said packing means.

5 6. A drilling device for use in a well and lowerable through a well tubing string which comprises, in combination, a retrievable support member provided with a fishing head engageable with a fishing tool, a weight member carried by said support member, a sleeve member slidably arranged on said support member, at least a pair of expandable blades pivotally connected to said sleeve member, frangible means releasably attaching said blades in inoperative position to said sleeve member, said support member enclosing the upper ends of said blades and being provided with upwardly inclined surfaces matingly engaging with corresponding inclined surfaces on said blades, and biasing means urging said sleeve upwardly relative to said support member for expanding said blades into operative position on release of said frangible means.

10 7. A device for use in a well and lowerable through a well tubing string which comprises, in combination, a retrievable support member, first and second sleeve members slidably arranged on said support member, a first pair of expandable drilling blades pivotally connected to said first sleeve member, a second pair of expandable reaming blades pivotally connected to said second sleeve member vertically spaced from said first pair, separate first and second frangible means releasably attaching said first and second pairs of blades respectively in inoperative

15 30 position to said first and second sleeve members, said support member enclosing the upper ends of said first and second pairs of blades and being provided with upwardly inclined surfaces matingly engaging with corresponding inclined surfaces on said first and second pairs of blades, and first and second biasing means urging said first and second sleeves upwardly relative to said support member for expanding said first and second pairs of blades into operative position on release of said first and second frangible means.

40 8. A device in accordance with claim 7 in which the second pair of blades are pivotally connected to said support member approximately 90° from said first pair of blades.

45 9. A drilling device for use in a well and lowerable through a well tubing string which comprises, in combination, a retrievable support member, a sleeve member slidably arranged on said support member, at least a pair of expandable drilling blades pivotally connected to said sleeve member, frangible means releasably attaching said blades in inoperative position to said sleeve member, said support member enclosing the upper ends of said blades and being provided with upwardly inclined surfaces matingly engaging with corresponding inclined surfaces on said blades, and biasing means urging said sleeve upwardly relative to said support member for expanding said blades into operative position on release of said frangible means.

50 55 10. A device in accordance with claim 9 in which the blades are provided with a reaming surface.
